(57) CLAIM

The ornamental design for a jersey album, as shown and described.

DESCRIPTION

FIG. 1 is a perspective view of my ornamental design for a jersey album.

FIG. 2 is a front elevation view of the jersey album of FIG. 1.

FIG. 3 is a rear elevation view of the jersey album of FIG. 1.

1.

FIG. 5 is a right side elevation view of the jersey album of FIG. 1.
